UNITED STATES PATENT OFFICE

2,605,069

NURSING BOTTLE HOLDER

John D. Gillaspy, Columbus, Ind., assignor to
Trenton Rice, Columbus, Ind.

Application February 13, 1947, Serial No. 728,283

1 Claim. (Cl. 248—103)

1

The invention relates to an adjustable holder, and more especially to a foldable portable nursing bottle holder.

The primary object of the invention is the provision of a holder of this character, a nursing bottle or the like can be detachably clamped in a manner so that it can be brought to a selected position when the said holder is mounted on an article of furniture, such for example, as a crib, bed or the like, to have the bottle in a convenient position, for the feeding of an infant, without liability of becoming displaced, accidentally dropping and getting out of feeding range of such infant.

Another object of the invention is the provision of a holder of this character, wherein it is unique and novel in construction, to permit the same to be easily fixed in any position desired convenient to the infant being fed, without liability of the said infant moving it out of the way, and such infant can be fed from either the right or the left side in a horizontal plane, as well as from any angle in the vertical plane, whether sitting up or lying down.

A further object of the invention is the provision of a holder of this character, wherein it can be folded up out of the way without removing it from the piece of furniture to which it is clamped, the clip of such holder being such that a firm grip is had upon the bottle and the latter can be tipped to any required angle regardless of how the child may handle or push the said bottle.

A still further object of the invention is the provision of a holder of this character, wherein it will not damage a bottle held thereby or mar the article of furniture to which it may be applied, and allowing adjustment from either side, top or bottom of such furniture, to any desired angle, with ease and dispatch, requiring no separate fixtures for attachment and will not mar or damage the article of furniture, being self-contained, and easily attached and removed at will.

A still further object of the invention is the provision of a holder of this character, wherein it is in the nature of a bracket, with an adjustment of one of its members to an arc of 180 degrees, while another member can be swung to approximately 340 degrees, and the clip for the bottle can rotate through an arc of 360 degrees, thus allowing the bottle itself to be moved horizontally 360 degrees and permitting it to be adjusted at any vertical position within an arc of 360 degrees, thereby effecting any angle of adjustment in any plane between the horizontal and the vertical.

2

A still further object of the invention is the provision of a holder of this character, which is simple in construction, thoroughly reliable and efficient in operation, strong, durable, neat in appearance, compact, readily and easily adjusted, applied and removed, with dispatch, conveniently folded, thereby requiring minimum space for its transportation and handling, and inexpensive to manufacture and install.

10 With these and other objects in view the invention consists in the features of construction, combination and arrangement of parts as will be hereinafter more fully described, illustrated in the accompanying drawing, which discloses the preferred embodiment of the invention, and pointed out in the claim hereunto appended.

In the accompanying drawing:

Figure 1 is a fragmentary vertical sectional view through a side portion of a crib, showing 20 the holder constructed in accordance with the invention applied for use.

Figure 2 is a top plan view of the holder in applied position.

Figure 3 is an elevation of the clamp or attaching end of the holder.

Figure 4 is a fragmentary sectional view taken on the line 4—4 of Figure 2 looking in the direction of the arrows.

Figure 5 is a sectional view taken on the line 30 5—5 of Figure 2 looking in the direction of the arrows.

Similar reference characters indicate corresponding parts throughout the several views in the drawing.

35 Referring to the drawing in detail, A designates generally a portion of the side-guard of a crib, cradle or the like, which may be of any construction, and is merely illustrated for a better understanding of the invention, as the latter can be applied to any suitable support or article of furniture that is acceptable for its application, and in this instance the said guard is provided with a horizontal run of a top rail 10, as usual to which the holder constituting the present invention as hereinafter described is applied.

The holder constituting the present invention, 50 comprises a substantially C-shaped attaching clamp or jawed attaching member 11, its jaws 12, and 13, respectively, are joined through the medium of a cross-web 14, while threaded through the jaw 12 is a manually operated adjustable binding screw 15 having a swiveled gripping button 16 within the clamp or member between the said jaws 12 and 13 thereof, while 55 tapped onto the outermost end of this screw is a finger engaging knob 17, it being held fast in any

suitable manner on the said screw. On the outer face of the jaw 13 is a pair of crosswise aligned substantially L-shaped bearings 18, which are made secure in any suitable manner and have disposed therebetween one end of a swinging arm 19, which is longitudinally straight and is turnable about a pivot bolt 20 passed transversely through the said bearings and end of the arm, the bolt being fitted with an adjustable binding knob 21, so that such arm 19 can be secured frictionally in any angular position within an arc of 180 degrees.

The arm 19 at its other end has connected therewith another or outer arms 22, which are swingingly joined by a pivot bolt 23 wearing an adjustable binding knob 24, so that this arm 22 can be held frictionally in any angular position within an arc of 340 degrees. The said arm 22 at the other end, namely the outermost end has connected thereto an L-shaped rotatable member 25, which is adjustably connected by a pivot bolt 26 carrying a binding knob 27, so that such member can be held secure in any desired rotated position.

The member 25 on its right angular terminal ear 28 has connected thereto a double-tined nursing bottle retaining clip 29, which at the shank 30 thereof is connected for adjustment by a pivot bolt 31 carrying a binding knob 32 to the said ear 28, the clip being covered by a resilient or pliable coating or sheathing 33, which prevents damaging the bottle, not shown, as may be clamped therein, and this coating or sheathing enables a firm grip upon the bottle while held to avoid accidental dropping from or shifting or slipping in the said clip. The tines of the clip 29 are resilient or inherently springy to assure a positive grip on the bottle, which is readily and easily placed in or removed therefrom with dispatch.

The coating or sheathing next to the knob 32 serves to more firmly bind the pivotal connection between the clip and the arm adjacent thereto together, so as to hold the clip in a fixed position under adjustment thereof.

In the use of the holder the clamp or jawed member 11 is brought into a position to straddle or saddle a support, as for example the rail 10, and made secure thereto by the screw 15, whereupon the arms 19 and 22 are adjusted to a selected angle with respect to each other, then the clip 29 is shifted to the desired relation thereto, and finally the bottle is mounted in the said clip, so that such bottle will be held in a convenient position with respect to an infant for the feeding of the same whether lying down or sitting up. The arms 19 and 22 have a wide range of ad-

justment with respect to each and the clamp and clip 11 and 29, respectively, also have a wide range of adjustment, so that the holder can be regulated for the convenient holding of the bottle in proper position for the easy feeding of an infant therefrom.

The holder when not in use can be readily swung out of the way and in a compact condition or when such holder is detached from a support it may be folded for storage or transportation within minimum space.

What is claimed is:

A nursing bottle holder comprising a pair of straight arms pivoted together end-to-end in alignment with each other, a clamp engageable with a support pivoted to the outermost free end of one arm for its swinging movement at substantially right angles to said support, a substantially L-shaped bracket forming extensions at right angles to each other, a pair of manually adjustable pivot means extending through each of said extensions in juxtaposed relation to each other, one of said pivot means pivotally connecting one extension to the outermost free end of the other arm, and a bottle clip pivotally connected by the other pivot means to the other extension for holding the said clip offset to the pair of arms and cooperating with the bracket to place the clip above and below said arms by following through arcuate paths of movements at right angles to each other, said bottle clamp having a plurality of resilient tines for positively gripping a bottle, said clamp having a shank and an aperture forming a part of said other pivot means and extending at a right angle to the plane of said tines whereby a bottle held by said clamp may be adjusted by both of said juxtaposed pivot means in vertical planes at right angles to each other, said tines and shank being covered with a resilient sheathing for resiliently gripping a bottle and forming a resilient pivotal connection between the shank and the said other extension.

JOHN D. GILLASPY.
